UNITED STATES PATENT OFFICE.

JAN WILLEM KLEINBENTINK, OF HOENS BROEK, LIMBURG, NETHERLANDS, ASSIGNOR TO NAAMLOZE VENNOOTSCHAP VEREENIGDE KOLENMAATSCHAPPIJ EN TER VOORTZETTING DER STEENKOLENZAKEN, GEDREVEN DOOR DE N. V. FURNESS' KOLENMAATSCHAPPIJ EN HOVEN EN HENNY'S HANDELMAATSCHAPPIJ, OF ROTTERDAM, NETHERLANDS, A COMPANY ORGANIZED UNDER THE LAWS OF THE NETHERLANDS.

MEANS FOR REFINING COAL SLIMES OR THE LIKE.

Application filed November 6, 1923. Serial No. 673,207.

To all whom it may concern:

Be it known that I, JAN WILLEM KLEINBENTINK, a subject of the Queen of the Netherlands, residing at Hoensbroek, Limburg, Netherlands, have invented certain new and useful Improvements in Means for Refining Coal Slimes or the like, of which the following is a specification.

The present invention relates to means for refining coal slimes or the like in such a manner that the slimes are brought into mixed relation with a substance capable of producing froth which when formed entraps coal particles and thus contains coal particles with a lower percentage of ashes than that of the original slimes. The present process is based on the fact that, when finely divided impure coal held in suspension in a froth-forming liquor is brought into intimate contact with a great number of small air bubbles distributed throughout the liquor, the relatively pure coal particles are entrapped and held by the air bubbles and rise into the layer of froth overlying the surface, whereas the particles having a comparatively high percentage of ashes remain in the liquor or settle to the bottom thereof.

In accordance with the invention the means for carrying this known method into practice comprise a mixing vat in which the slimes are thoroughly intermixed with water and with a froth-producing substance and into which air is introduced, in combination with a froth-containing vat in communication with the mixing vat and permitting the froth with the relatively pure coal particles adhering thereto to separate from the particles having a comparatively high percentage of ashes, both vats being also in communication with each other through a second duct by which part of the liquor which is transferred from the mixing vat into the froth-containing vat returns into the mixing vat. By these means an efficient circulation is procured so that the mixture is repeatedly subjected to the action of the mixing and agitating means, the result being that the relatively pure coal particles ascend into the aerated layer of froth as completely as possible.

The annexed drawing illustrates diagrammatically and by way of example only an apparatus in accordance with the present invention, Figure 1 being a vertical sectional view, and Figure 2 a plan view thereof. 55

The coal slimes, water and a froth-producing substance are continuously admitted into the mixing vat *b* through a pipe *a*. If desired, however, the froth-producing substance could be introduced through a separate pipe *c*. The mixing and agitating apparatus comprises a spindle *d* provided with blades *e* or wings set in such a manner that, when the spindle *d* rotates in a given direction, the liquor is mixed and agitated and it is transferred through openings *f* near the bottom into the frothing vat *g* surrounding the mixing vat. In the froth-containing vat *g* the velocity of flow of the liquor is reduced to such an extent that the air bubbles 60 and the relatively pure coal particles entrapped thereby rise to the surface, whereas the particles having a comparatively high percentage of ashes settle and are flushed out through a pipe *h*. Part of the liquid is 65 discharged through an overflow pipe *i*, the remainder of the liquid returning into the mixing vat *b* through holes *k* so as to be again subjected to the action of the agitating and mixing apparatus and the air bubbles can again entrap and hold the relatively pure coal particles still present. This circulation of the liquor is a typical feature of the present invention and is indicated by 70 arrows in Figure 1. 75

The froth is removed from the froth-containing receptacle in any suitable manner and may be subjected to subsequent treatment if so desired.

From the drawing it follows that the wall 80 of the mixing vat forms a frustum of an upwardly pointing cone, whereas the wall of the frothing vat forms a co-axial frustum of a cone pointing downwards. This construction has certain advantages, not only 85 as far as the formation of froth is concerned, but also with a view to the easy ascent of the air bubbles to the surface of the liquid in the froth-forming vat.

As far as the operation of the apparatus 100

is concerned, it is immaterial how the froth is produced. In practice the coal slimes are ordinarily thinned with water and the resulting liquor mixed with air. Obviously, however, the described apparatus could be used with equal advantage when another liquid or another gas or gas-forming substances is or are used. The apparatus is also suitable for refining ore slimes.

19 It is not necessary for the froth vat to be arranged around the mixing vat, but it is essential that both vats be in communication with each other in such manner that the liquid therein can circulate. Consequently, 15 the vats could be disposed side by side or in descending order.

20 In the example illustrated the mixing and agitating apparatus simultaneously acts as a pump which effects the required circulation. It will, however, be understood that these actions could be effected by means independent the one of the other. For instance, the pump could be disposed in the froth-containing vat between the openings 25 *f* and *h*. These and other modifications may be found desirable to meet the requirements of use and they fall within the nature and scope of the invention as expressed in the

accompanying claims when broadly construed.

30

Having now particularly described and ascertained the nature of my said invention and in what manner the same is to be performed, I declare that what I claim is:—

35 In an apparatus for concentrating coal slimes and ores in accordance with the froth flotation process, a froth forming vat, the width of which increases from the bottom to the top, an agitating box within said vat, the width of the box decreasing from the 40 bottom to the top, with the upper edge of the box above the upper edge of the vat, the box being in communication with the vat through an exit opening near the bottom and an inlet opening above the bottom and below the upper edge of the vat, an agitating means arranged in the box and rotatable about a vertical axis to force the material in the agitating box through the exit opening 45 into the vat, the inlet opening permitting the return of the material from the vat to the agitating box.

50 In testimony whereof I affix my signature.

JAN WILLEM KLEINBENTINK.
